Inventor,

Henry B. Walbridge.

UNITED STATES PATENT OFFICE.

HENRY B. WALBRIDGE, OF BROOKLYN, NEW YORK, ASSIGNOR TO ALICE C. WALBRIDGE, OF WASHINGTON, DISTRICT OF COLUMBIA.

IMPROVEMENT IN MODES OF ATTACHING BUTTONS, &c., TO FABRICS.

Specification forming part of Letters Patent No. 133,273, dated November 19, 1872.

To all whom it may concern:

Be it known that I, HENRY B. WALBRIDGE, of the city of Brooklyn, in the county of Kings and State of New York, have invented certain new and useful Improvements in Attaching Buttons, Hooks, and similar articles to Clothing; and I do hereby declare that the following is a full, clear, and exact description of the same, reference being had to the accompanying drawing making a part of this specification.

The object of my invention is to dispense with the use of thread, by which buttons, hooks, clasps, &c., are ordinarily attached to clothing; and it consists in making the metallic object to be attached with a broad flat disk, which is coated with shellac and applied to the garment. Heat is then applied, when the two become firmly united together. A convenient way of applying the heat is by an ordinary tailor's iron, but any way which will melt the shellac and cause it to penetrate the fibres of the cloth will answer. The union is very firm, for shellac is unaffected by moisture, and its adhesion to both the metal and the fabric is very close. The invention is particularly useful for the attachment of large metallic hooks, clasps, or buttons, to heavy over-garments, where the strain is great; also to attach suspender hooks or buttons, which are extremely liable to come off at the most inconvenient times. In my invention when the hook comes off the cloth comes with it. The buttons, hooks, or clasps can be made as ornamental as is desired, and of as expensive material, as it is immaterial what metal is used. The es-

sence of the invention does not consist in the shape of the hook, button, or clasp, provided it has a surface for the adhesion of the shellac, nor in the material of which it is composed; but solely in the use of shellac to form the connection between the broad metallic surface of the button or hook and the fabric to which it is joined by the application of heat.

In the accompanying drawing I have illustrated various modes of applying my invention. Figure 1 represents a hook attached to the outer surface of the cloth. Fig. 2 represents a sectional view of the same. Fig. 3 represents a hook with a double disk, embracing the fabric on both sides to give a very strong junction. In Fig. 4 the disk of the hook is included between two thicknesses of fabric, when it is desired not to have the metallic disk visible. Fig. 5 shows a button with a broad base or disk attached in a similar manner. Fig. 6 is another variety of the same.

I am aware that shellac has been used for uniting the ends of curtain-cord, as well as in cementing together the parts of certain articles of jewelry. This I do not claim; but

What I claim as my invention, and desire to secure by Letters Patent, is—

The mode of attaching hooks, buttons, or equivalent fastenings to garments by means of shellac and the application of heat, substantially as specified.

HENRY B. WALBRIDGE.
